UNITED STATES PATENT OFFICE.

WILLIAM J. RYAN, OF SAPULPA, OKLAHOMA.

COMBINED VENTILATOR.

1,186,842.

Specification of Letters Patent. Patented June 13, 1916.

Application filed October 3, 1913. Serial No. 793,221.

To all whom it may concern:

Be it known that I, WILLIAM J. RYAN, a citizen of the United States, residing at Sapulpa, in the county of Creek and State 5 of Oklahoma, have invented new and useful Improvements in Combined Ventilators, of which the following is a specification.

This invention is an improved window ventilator which also forms a bay attachment to a window, the object of the invention being to provide an improved ventilator which also forms a window screen and a bay or lookout attachment and which is adapted to direct a current of air without 10 15 20 25 30 35 40 45 50 55 60 65 70 75 80 85 90 95 100 105

building, into the same, from either direction and also to prevent dust from being blown into a window by the wind.

The invention consists in the construction, combination and arrangement of devices

hereinafter described and claimed.

In the accompanying drawing: Figure 1 is a perspective view of the window ventilator, screen, bay or lookout showing the same attached for use. Fig. 2 is a horizontal sectional view of the same on the plane indicated by the line *a—a* of Fig. 1.

In accordance with my invention I provide a frame 1 which comprises a triangular bottom or floor 2, a correspondingly-shaped top or roof 3 and a vertical post 4 which connects the outer corner or apices of the bottom and top. The frame is also here shown as provided with ornamental cresting 5 at the top but this may be omitted if preferred. Under the bottom of the frame is a supporting bracket 6 which may be attached to the outer side of the wall of a building to support the frame at the outer side of the lower portion of a window as shown in Fig. 1. The bottom and top of the frame are also secured to the frame of the window by means of suitable hooks 7 or other suitable attaching device may be used if preferred within the scope of my invention.

In the sides of the frame, which converge outwardly to the post 4, are screens 8 each of which comprises a suitable rectangular frame 9 and a covering 10 of iron gauze or other suitable foraminous material. One side of each screen is hinged to the post 4 as at 11 and the opposite side of each screen is connected to one side of the window frame by a hook 12. The frame 1 with its screens 55 which form its outwardly converging sides may be readily attached to and detached

from an ordinary window as will be understood.

I also provide a glazed sash 13 which forms a movable partition and is arranged 60 in an upright position in the frame, its outer side being hinged to the post 4 and the said sash being adapted to be turned angularly in the frame so that it may lie against either of the screens 8 or may be arranged 65 at a point midway between the said screens and at right angles to the wall of the house. Suitable means are provided to secure the said glazed sash or partition in any desired position in the frame and for the purposes 70 of this specification the said glazed sash is shown provided at its inner side with a bolt 14 which may be engaged with any of the openings 15 in the bottom of the frame, to hold the sash in adjusted position.

When the partition wall or sash 13 is arranged midway between the frames a current of air from without, blown directly against the wall of the building, will be caused to enter the room or building through 80 the window when the wind is blowing parallel with the wall on which the ventilator is used the sash 13 should be turned in the opposite direction from that in which the wind is blowing and to bear against one of 85 the screens 8 and thus caused to act as a deflector to direct the wind or current of air into the room through the window. When it is desired to exclude dust during 90 a wind storm without excluding air from the window the sash 13 should be turned against the screen 8 on which the wind is blowing, and the said sash will then serve as a deflector to change the direction of the wind as it strikes the frame and divert it 95 outwardly from the wall of the building and thus prevent dust from entering the window through the other screened side of the frame. My improved ventilator also forms a bay attachment or lookout attachment for 100 a window as will be understood. When the device has been detached from the window the screens 8 and the glazed sash 13 may be folded against each other as will be understood.

While I have herein shown and described a preferred form of my invention I would have it understood that changes may be made in the form, proportion and construction of the several parts without departing 110 from the spirit of my invention and within the scope of the appended claim.

Having thus described my invention, I claim:

A ventilator consisting of a triangular bottom member and a triangular top member, a pair of rectangular frames, a vertical post to which the outer ends of said frames are hinged, a deflector hingedly connected at its outer end to said vertical post so as to swing between said frames, a support for the bottom member to hold its opposite edges against the edges of said frames, means for fastening said frames at their ends to the sides of an opening, said top member resting upon the upper edges of said frames and

engaging said posts, said bottom member being formed with an arcuate series of openings, and means carried by said deflector and adapted to engage any of said openings so as to hold said deflector in adjusted position and simultaneously hold said bottom member against displacement. 15 20

In testimony whereof I affix my signature in presence of two witnesses.

WILLIAM J. RYAN.
